MULTIPLE FUSE PLUG

John B. Glowacki, Chicago, Ill.

Application January 22, 1934, Serial No. 707,647

19 Claims. (Cl. 200—125)

The present invention relates to a multiple screw type fuse plug having a spring controlled contact head for resiliently holding the contact pin seated in any one of a plurality of contact 5 sockets which are connected with the inner ends of a plurality of radially directed fuse elements which, in one form of the invention, are positioned in a renewable multiple fuse supporting barrel unit which is removably clamped on a

10 screw type base plug.

It is an object of this invention to provide a multiple type of fuse plug which is so constructed that a single contact member may be selectively set to connect up with any one of a plurality of 15 fuse elements engaged within the fuse plug.

It is also an object of this invention to provide a multiple screw type fuse plug having a renewable type of fuse carrying barrel whereby a new multiple type of fuse and a supporting 20 barrel may be engaged between a plug unit and contact head when the first series of fuse elements have been used.

It is a further object of this invention to provide a multiple screw type fuse plug having a 25 plurality of visible fuse elements so positioned that any one of the elements may be selectively connected in a circuit by means of an adjustable contact means.

It is furthermore an object of this invention 30 to provide an improved type of multiple fuse plug having a ring fuse unit provided with a plurality of radially directed fuse elements, any one of which is adapted to be connected in a circuit by means of a spring controlled adjustable contact

35 member.

Another object of the invention is to provide a multiple screw type fuse plug wherein a plurality of radially positioned fuse elements are engaged by means of a plurality of contact sockets 40 cured in order in a disc to permit a contact pin carried by a spring-controlled rotatable knob or head to be removably engaged in any one of the contact sockets for the purpose of selectively connecting up one of the fuse elements in a 45 circuit.

It is an important object of this invention to provide an improved type of a multiple fuse plug wherein a renewable barrel containing a plurality of fuse elements is removably engaged 50 between a screw base plug and a head which is rotatable to permit a contact member to be selectively moved into engagement with any one of the fuse elements until all of the fuse elements 55 have been blown, after which the renewable

barrel may be replaced by a new one containing a new set of fuse elements.

Other and further objects of this invention will be apparent from the disclosures in the accompanying specification and drawings. 5

The invention (in a preferred form) is illustrated in the drawings and hereinafter more fully described.

On the drawings:

Figure 1 is an elevational view of a multiple 10 screw type fuse plug embodying the principles of this invention.

Figure 2 is an enlarged top plan view of the fuse plug.

Figure 3 is an enlarged longitudinal middle 15 section of the fuse plug with parts shown in elevation.

Figure 4 is a transverse sectional view taken on line IV—IV of Figure 3, to show the fuse ring unit constructed of a plurality of fuse elements. 20

Figure 5 is a modified form of multiple fuse element unit in the form of a continuous ring having a plurality of radially disposed fuse elements integrally formed thereon.

Figure 6 is a sectional detail view taken on 25 line VI—VI of Figure 3 and illustrating the bottom view of the contact head of the fuse plug.

Figure 7 is an enlarged fragmentary detail section of the fuse plug taken on line VII—VII of Figure 2 with parts shown in elevation. 30

Figure 8 is a top plan view of the apertured supporting disc for carrying the contact sockets in position between the fuse elements and the contact pin of the fuse plug.

Figure 9 is a transverse detail section taken 35 on line IX—IX of Figure 8 and showing one of the contact sockets projecting upwardly above the top surface of the supporting disc.

Figure 10 is a side elevation of the flanged contact sleeve or ferrule removed from the removable fuse barrel unit of the fuse plug. 40

Figure 11 is a sectional view of the fuse plug similar to that illustrated in Figure 4 but having the fuse elements removed.

Figure 12 is a longitudinal central sectional 45 view of a modified form of multiple screw type fuse plug, of a type in which the entire fuse plug must be replaced when the plurality of fuse elements have been blown.

As shown on the drawings:

The improved multiple screw type fuse plug 50 comprises a base or plug section 1 constructed of insulating material and having integrally formed around the upper portion thereof an outwardly extending knurled flange 2. Seated around 55

- the lower portion of the base plug 1 is a spirally threaded sleeve or screw shell 3, the outer end of which is flanged inwardly and is molded into the material forming the base plug 1. Integrally formed on the inner end of the screw shell 3 is a ring or sleeve 4 which is also molded into the material forming the base plug 1 and projects upwardly and has the end thereof bent inwardly to provide a contact flange 5 which is disposed 5 against the top surface of the base plug 1 as clearly illustrated in Figs. 3 and 7. A recess or pocket 6 is formed in the upper central portion of the base plug 1 and is also provided with an axial passage in which the enlarged end 7 of a 10 guide and connecting sleeve is secured. The enlarged section 7 of the tubular sleeve is provided with a knurled section 8 to hold the sleeve against rotation within the base plug. An upper sleeve section 9 is integrally formed with the lower section 15 7 and is formed with an intermediate threaded portion 10. The reduced section 9 of the connecting sleeve projects upwardly above the upper end of the base plug 1 through the recess or pocket 6.
- 25 Slidably projecting through the sleeve section 9 is a contact post 11, the lower end of which is positioned to project into the enlarged sleeve section 7 and has engaged therearound a control spring 12 the inner end of which seats against a shoulder within the sleeve section 7 while the outer end of said spring seats against the head 13 of a screw 14 which is removably threaded into a threaded opening in the lower end of the contact post 11, as clearly illustrated in Figure 3.
- 30 Secured in the lower end of the sleeve section 7 is a tubular contact head 15 provided at its outer end with a retaining flange 16 which serves to hold an insulation washer 17 in position around an extending portion of the sleeve section 7 and 35 in contact with the lower end surface of the base plug 1 as clearly illustrated in Figure 3.
- 35 Removably secured or clamped against the flange 5 on the inner end of the base plug 1 is a renewable barrel unit in which the fuse elements 40 of the fuse plug are carried. The renewable barrel unit comprises a body or core 18 formed of a suitable insulating material which is molded to form and has a ring of chambers or pockets 19 and a plurality of radially positioned seats or de- 45 pressions 20 which project inwardly from the tops of the inner sides of the chambers 19, as clearly illustrated in Figure 11. Each of the depressions 20 is provided with a hole 21. As also shown in Figure 11, a circular seat 23 is provided 50 in the top of the barrel core unit 18 to receive a top contact flange 24 seated therein. The contact flange 24 is integrally formed on the upper end of a conducting sleeve or collar 25 having a plurality of binding openings 26 formed therein as clearly 55 illustrated in Figure 10. The conductor sleeve 25 is molded in the material forming the barrel core unit 18 and is securely bound in position by means of the insulating material filling in the openings 26 to bind the conductor sleeve 25 in 60 place. Integrally formed on the lower end of the conductor sleeve 25 is an inwardly directed lower contact flange 27 which is so positioned that it will tightly seat against the contact flange 5 of the base plug as clearly illustrated in Figure 3.
- 65 70 The barrel core unit 18 is provided on its lower end with an internally threaded extension or collar 28 which, when the barrel unit is in position upon the base plug, projects into the chamber 6 and is threaded downwardly on the threaded section 10 of the coupling sleeve or

75 connector which is secured axially within the base plug 1. The renewal barrel may thus be threaded downwardly on the threaded sleeve 10 until the lower contact flange 27 of the barrel unit is brought into tight contact with the upper contact flange 5 of the base plug.

80 Formed around the molded barrel core 18 is a metal casing or housing 29 the outer peripheral surface of which is knurled as clearly illustrated in Figure 1. The casing 29 is provided with a plurality of vent openings or holes 30 positioned to communicate with the space above the top surface of the core 18 of the barrel unit. The lower margin of the barrel casing 29 is deflected inwardly beneath the bottom surface of the core 15 18 and then downwardly to provide a supporting flange 31 which projects into a peripheral groove provided in the upper portion of the base plug above the base plug flange 2 as clearly illustrated in Figure 3. In the renewable barrel unit 20 above the explosion chambers 19 are a plurality of fuse units or elements each comprising a segment-shaped section 32, an apertured head section 33 and a reduced or restricted melting strip or stem 34 which integrally connects the sections 25 32 and 33 as clearly illustrated in Figure 4. The various fuse elements are positioned with the segment-shaped sections arranged adjacent one another to form a ring having the melting strips 34 projecting radially inwardly with the head 30 sections 33 of the fuse elements seated in the receiving recesses or depressions 20 (Figure 11) so that the openings or apertures in the head sections 33 register with the holes 21 provided in the core 18 of the renewable barrel. The fusing 35 strips 34 are so positioned that they project diametrically across the tops of the explosion chambers 19. Seated within the upper portion of the circular recess or groove 23 of the barrel core 18 above the shanks or segment-shaped portions 32 40 of the fuse elements is a circular fiber washer 35.

45 Seated in the barrel casing 29 upon the upper end of the barrel core 18 and upon the filler or washer 35 is a circular fiber plate or disc 36 having a plurality of sight openings 37 arranged in a circle as clearly illustrated in Fig. 8. The fiber plate 36 is also provided with a circular arrangement of openings to the inside of the openings 37 and have secured therein a plurality of contact sockets 38 each of which is provided 50 with a downwardly projecting contact pin or stem 39. As illustrated in Figure 9, it will be noted that one or more of the contact sockets 38 project above the top surface of the disc or plate 36 to permit the same to project into apertures 40 (Figure 3) provided in a clear mica window disc 41 seated on the top surface of the fiber plate 36. The projection of one or more of the projecting ends of the contact sockets 38 into the openings 40 of the mica disc 41 holds 55 said disc against rotation. As illustrated in Figure 3, the upper margin of the barrel casing 29 is deflected inwardly to form a retaining flange 42. As clearly illustrated in Figure 8, the fiber plate 36 is provided with a central opening 43 60 which registers with a central opening in the mica disc 41 to permit the plate and said mica disc to be engaged over the upper end of the reduced section 9 of the locking sleeve which bolts the renewable barrel to the base plug of 65 70 the device.

75 The contact post 11 projects upwardly through the renewable barrel unit and is provided with a diametrical passage in which the arm or shank portion 44 of a contact finger or pin 45 projects. 75

The contact pin 45 and its shank 44 are molded within a contact head or knob 46 which in turn is molded on the upper peripherally grooved end of the contact post 11. The contact head or knob 46 is provided with a peripherally knurled flange 47 to facilitate turning of the head or knob when the same is pulled slightly upwardly against the action of the spring 12 to permit the contact point 45 to be engaged through the apertured mica disc into any one of the contact sockets 38.

Figure 12 illustrates a modified form of multiple screw type fuse plug in which the parts which are identical with the parts of the fuse plug as described in connection with Figures 1 to 11 inclusive, are designated with corresponding reference numerals.

In the modified form of fuse plug the reference numeral 48 indicates a plug core or body constructed of insulation composition matter. The core or body 48 is provided in its upper end with a circular row of explosion pockets or chambers 49 while the lower end of the body is provided with a circular row of depressions or holes 50. Molded axially in the body or core 48 is a guide tube or sleeve comprising an enlarged lower tubular section 51 and an integral reduced upper section 52, the upper end of which projects upwardly above the upper end of the body 48 through several openings provided in the insulation plate 36 and in the mica window or disc 41. The exterior surface of the lower cylindrical section 51 of the axial sleeve is provided with a knurled surface 53 which serves to act as a binding means for holding the guide sleeve in position against movement with respect to the body 48. The core or body 48 is molded within a casing or housing 54 with the upper end of the housing projecting in or being molded within the material forming the upper part of the core. The embedded upper end of the housing 54 has the upper margin thereof deflected outwardly to provide a contact flange 55. Formed in the upper embedded portion of the housing 54 are a plurality of apertures or openings 56 which serve as a binding means permitting the material forming the core or body 48 to seat in said openings to hold the upper flanged portion of the body 48 securely in place. The upper end of the core or body 48 is also provided with fuse element depressions or seats 20, the holes 21 and the grooves 23 similar to the arrangement illustrated in Figure 11 of the drawings.

Engaged around the upper flange portion of the core or body 48 is an externally knurled retaining collar 57 constructed of metal. The metal retaining collar 57 is provided with a plurality of vent openings 58 positioned at substantially the level of the top surface of the body 48 in order to permit the escape of gases and the like from the combustion chambers 49 outwardly between the top surface of the body 48 and the bottom surface of the plate 36.

The lower margin of the collar 57 is deflected inwardly to form a lower retaining flange 59 and the upper margin of the collar 57 is deflected inwardly to provide a top retaining flange 60 for holding the insulation plate 36 and the mica disc 41 in position.

Slidably engaged in the guide sleeve of the fuse plug is the contact post 11 having the contact head 46 molded thereon, similar to the arrangement illustrated in Figure 3. The contact head 46 has embedded therein the contact pin 45 which is adapted to be selectively engaged

in any one of the plurality of contact sockets 38. The contact head 46 is resiliently held in position against the top surface of the mica window 41 by means of a coiled spring and a headed screw member similar to the arrangement illustrated in Figure 3.

The lower margin of the casing or housing 54 is deflected inwardly to provide a bottom retaining flange 61 which is provided with a plurality of openings which register with the holes 50. Securely engaged around the lower reduced portion of the housing 54 is a shell 62 the upper end of which seats against a shoulder 63 forming a part of the housing 54 while the lower end of the screw base is deflected inwardly to provide a retaining flange 64 having a plurality of round or cylindrical sleeves or shells 65 struck inwardly therefrom to project through the openings in the base flange 61 and into the body recesses or holes 50.

Secured in the lower end of the guide sleeve section 51 is a flanged contact head 66 which holds an insulation washer 67 in position against the lower retaining flange 64 of the screw base 62.

Figure 5 of the drawings illustrates a modified form of fuse element unit which, if desired, may be used in place of the plurality of radially arranged fuse elements 32-33-34 illustrated in Figure 4. The modified form of fuse element unit comprises a continuous fuse ring 68 having 30 integrally formed on the inner margin thereof a plurality of inwardly or radially directed fusing or melting sections 69 terminating in fuse element heads 70 provided with apertures 71.

The operation of the fuse plug is as follows:

With a loaded renewable fuse barrel engaged on the threaded portion 10 of the guide sleeve and with the contact post 11 and contact head 46 in position as illustrated in Figure 1, the screw 40 base 3 is screwed into a fuse plug socket by means of the knurled flange 2 until the contact head 46 is brought into contact with the contact member within the fuse plug socket. With the contact pin 45 engaged in one of the contact sockets 38 one of the fuse elements 34 is properly connected in the electric circuit.

When a short circuit condition is encountered, or when an excessive amount of current passes through the circuit, the fuse element 34 connected up in the circuit will melt or blow into the explosion chamber 19 beneath the fuse element and the products of combustion resulting from the blowing of the fuse are permitted to escape upwardly between the top surface of the barrel core 18 and the insulation plate 36 outwardly through the vent holes 30.

By looking through the mica windows 41 an attendant can easily tell which of the fuses has been blown and if the fuse in circuit has been blown it is only necessary for the operator to pull outwardly on the contact head 46 against the action of the spring 12 to move the contact pin 45 out of contact with the contact socket 38 of the blown fuse element. By rotating the contact head 46 when raised, the contact pin 45 may be lowered into another contact socket 38 with the pin projecting through the respective opening 40 provided in the mica window 41. In this manner a good or unblown fuse element is 70 connected in circuit. When all of the fuse elements contained within the renewable barrel have been blown, the fuse plug is removed from its socket and a screw driver may be inserted through the contact head sleeve 15 to engage the 75

screw head 13 to rotate the same thereby forcing out the contact head or ferrule 15 and at the same time releasing the contact post 11 to allow said post and the contact head 46 to be removed. With the removal of the contact post and head the used renewable fuse barrel unit is unthreaded from the threaded section 10 of the axial sleeve and is replaced by means of a new barrel unit containing a set of new fuse elements.

10 It will of course be understood that the fuse elements contained in the renewable barrel may be of a type illustrated in Figure 4 or of the unitary multiple element type illustrated in Figure 5.

In the form of fuse plug illustrated in Figure 15 12, there is no renewable fuse element barrel so that when all of the fuse elements of this type of fuse plug have been blown, it is, of course, necessary to replace the entire fuse plug by a new one.

20 It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. A multiple screw type fuse plug comprising a screw type body unit, a contact sleeve unit 30 therein, a spring controlled contact post slidably mounted in the sleeve unit, a head formed on the projecting end of the contact post, a plurality of fuse elements in said body unit, an apertured plate engaged against one end of the body 35 unit, a plurality of contact sockets in said plate and engaging the fuse elements, an apertured transparent disc engaged against one side of said plate, and a contact member connected with the contact post and projecting from the contact 40 head through the apertured transparent disc into contacting engagement with a selected one of said contact sockets.

2. A multiple screw type fuse plug comprising a body unit, an apertured screw shell engaged 45 theron, a plurality of apertured fuse elements in the body unit and communicating with the screw shell, a plurality of contact sockets arranged to project through the fuse elements, a transparent covering having openings therein to fit over said 50 contact sockets, and contact means movable longitudinally and rotatably with respect to the body unit for selective removable engagement with any one of said contact sockets.

3. A multiple screw type fuse plug comprising 55 a base, a contact sleeve secured thereto and projecting therefrom, a barrel unit removably engaged on the contact sleeve in contact with the base unit, a plurality of fuse elements in the barrel unit, a plate secured in the barrel unit, a plurality of contact sockets supported by the plate and having contacting engagement with the fuse elements, an apertured transparent disc in the barrel unit covering said plate with the apertures in the disc registering with the contact 60 sockets, a spring controlled contact post slidably and rotatably engaged in said sleeve, a contact head secured on the projecting end of the contact post and disposed to the outside of the transparent disc, and a contact member in the contact head for removable engagement with any selected one of the contact sockets when the contact post and the contact head are moved longitudinally and rotatably with respect to the barrel unit.

75 4. A multiple screw type fuse plug comprising

a base unit, a screw shell engaged thereon and projecting into the base unit and having a plurality of openings therein for binding different portions of the base unit together, a sleeve secured in the base unit and projecting therefrom, 5 an insulation washer engaged on one projecting end of the sleeve and in contact with one end of the base unit, a contact means engaged in the sleeve for holding the insulation washer in position, a barrel unit having a plurality of explosion 10 chambers therein, said barrel unit removably engaged on the sleeve in contact with the screw shell, a plurality of fuse elements in the barrel unit, apertured means embedded in the barrel unit and affording a contact between the fuse 15 elements and the screw shell of the base unit, an insulation plate in the barrel unit, a plurality of contact sockets in the insulation plate having contacting engagement with the fuse elements, an apertured transparent disc in the barrel unit 20 covering the insulation plate and having the apertures registering with said contact sockets, a spring controlled contact post slidably and rotatably engaged in the sleeve and projecting through the barrel unit, a contact head on the 25 contact post, and a contact pin connected with the contact post and partially embedded in the contact head, said contact pin projecting from the contact head into a selected removable position in contact with one of the contact sockets. 30

5. A multiple screw type fuse plug comprising a screw base unit, a chambered barrel unit removably engaged with the base unit and having vent openings therein, a plurality of fuse elements in the barrel unit, a plurality of contact 35 members in the barrel unit connected with the fuse elements, an apertured transparent disc in the barrel unit having the apertures thereof registering with the contact members, a spring controlled contact unit slidably and rotatably engaged with the base unit and with the barrel unit, and a contact pin carried by the contact unit for selective engagement through the openings in the transparent disc for contact with a selected contact member and the fuse element connected 45 therewith.

6. A multiple fuse plug comprising a body unit, a contact unit slidably and rotatably connected therewith, a wheel type fuse element comprising a plurality of fuse members engaged in the body 50 unit, and contact sockets projecting through the fuse members for selective engagement by the contact unit when the contact unit is pulled outwardly and rotated.

7. A multiple fuse plug of the class described 55 including in combination a fuse unit comprising a radially split rim section having a plurality of apertured fusing members radially projecting inwardly therefrom and terminating short of the center.

8. A multiple fuse plug of the class described 60 including in combination a body unit, a wheel type fuse unit therein comprising a circular rim section having a plurality of apertured fuse members radially formed thereon, contact sockets 65 projecting through the apertured fuse members, and an adjustable contact means connected with the body unit and longitudinally and rotatably movable into selective telescopic engagement with the contact sockets.

9. A multiple fuse plug including in combination an apertured body unit, a plurality of fuse elements therein, an adjustable contact means connected with the body unit, and a contact unit 70 engaged in said body unit and comprising an 75

- apertured insulation plate, a plurality of contact sockets secured therein for selective engagement by the contact means, and contact pins formed on the contact sockets and engaging the fuse elements in the body unit.
- 5 10. A multiple fuse plug comprising in combination a body unit having a plurality of apertured fuse elements therein, an apertured insulation plate in said body unit, a plurality of contact sockets projecting through the apertured insulation plate, contact pins on said contact sockets projecting through the apertures in the fuse elements, an apertured transparent disc in the body unit positioned with the apertures in the transparent disc registering with the contact sockets, and a contact means adjustably connected with the body unit and adjustable for selective contact through the apertures in the transparent disc with the contact sockets.
- 10 15 20 25 30 35 40 45 50 55 60 65 11. In a multiple fuse plug of the class described, a renewable barrel unit comprising a body having a plurality of explosion chambers therein, a shell engaged around the body and having a plurality of vent openings therein, a flanged sleeve molded in the body and having a plurality of openings therein to receive material for binding the different sections of the body together, a plurality of apertured fuse elements seated in the body and projecting across the explosion chambers thereof, an apertured insulation plate within said casing and in contact with the body, a plurality of contact sockets secured in the insulation plate and projecting through the openings in the fuse elements, and an apertured transparent disc in the casing adjacent the insulation plate, with the apertures in said disc registering with the contact sockets to receive one of the contact sockets projecting therethrough to hold the apertured disc in place.
12. A multiple fuse plug comprising in combination a body unit having a plurality of fuse means therein, and a contact unit adjustably engaged in the body unit for selective engagement with the fuse means, said contact unit comprising a contact post slidably and rotatably engaged in the body unit, a control spring engaged around said post, a retaining screw engaged in one end of the post and affording a seat for the control spring, a control head on a projecting end of the contact post, and a contact pin engaged with the contact post and embedded in the contact head with a portion of said pin projecting from the head for selective engagement with the fuse means in the body unit.
13. A multiple screw type fuse plug comprising a screw plug unit, a plurality of fuse elements therein, an apertured plate engaged against one end of the screw plug unit, a plurality of contact sockets secured in said plate and projecting therefrom into engagement with the fuse elements, and a contact means movably engaged with the screw plug unit for selective engagement with any one of the contact sockets.
14. A multiple screw type fuse plug comprising a screw plug unit, a plurality of fuse elements therein, an apertured plate engaged against one end of the screw plug unit, a plurality of contact
- sockets secured in said plate and engaging the fuse elements, an apertured transparent disc seated on said plate with the contact sockets projecting into the disc apertures, and a contact means movably engaged with the screw plug unit for selective engagement with any one of the contact sockets.
15. A fuse plug of the class described including in combination a base, a contact sleeve secured therein and projecting therefrom, a barrel unit 10 removably engaged on the contact sleeve, fuse elements in the barrel unit, a post in said sleeve having one end projecting from the sleeve, a contact member on the projecting end of the post, and spring means between the sleeve and said 15 post for resiliently holding the contact member in engagement with one of said fuse elements.
16. A fuse plug of the class described including in combination a base unit, a screw shell engaged thereon and having one end embedded in the base 20 unit, said embedded end of the shell having a plurality of openings therein filled with the material forming the base unit for binding different portions of the base unit together and for holding the shell locked against rotation on the base unit. 25
17. A fuse plug of the class described including in combination a base unit, a screw shell engaged thereon and having an apertured portion embedded in the base unit with the apertures filled with the material forming the base unit for binding 30 different portions of the base unit together and for holding the shell locked against rotation on the base unit, a contact flange formed on the apertured portion of the screw shell seated against one end of the base unit, a barrel unit, contact 35 means for removably holding the barrel unit on the base unit, fuse elements in the barrel unit for connection with the contact means, an apertured conducting sleeve embedded in the barrel unit in contact with the fuse elements, said conducting sleeve having the apertures therein filled with the material forming the barrel unit, and a contact flange formed on the conducting sleeve and seated against one end of the barrel unit in contact with the contact flange of the apertured 40 portion of the screw shell.
18. A multiple fuse plug comprising, in combination, a body unit having a plurality of apertured fuse elements therein, an insulation plate in said body unit, a plurality of contact members 50 projecting through the insulation plate and through the apertured fuse elements, an apertured transparent disc covering the insulation plate and having the apertures registering with the contact members, and a contact means adjustably projecting from the body unit and selectively adjustable for contact with the contact members. 55
19. A multiple fuse plug including in combination a body unit, a plurality of fuse elements 60 therein, an adjustable contact means projecting from the body unit, an insulation plate in the body unit, and a plurality of contact members projecting through the insulation plate into engagement with the fuse elements for selective 65 engagement by the contact means.

JOHN B. GLOWACKI.
